UNITED STATES PATENT OFFICE

HARLOW M. DAVIS, OF BUFFALO, NEW YORK

DESIGN FOR A MERCHANDISE DISPLAY RACK

Application filed October 11, 1932. Serial No. 45,312. Term of patent 7 years.

To all whom it may concern:

Be it known that I, HARLOW M. DAVIS, a citizen of the United States, residing at Buffalo, in the county of Erie and State of New York, have invented a new, original, and ornamental Design for a Merchandise Display Rack, of which the following is a specification, reference being had to the accompanying drawing, forming a part thereof.

The drawing is a perspective view of the merchandise display rack showing my new design.

I claim:

The ornamental design for a merchandise display rack as shown.

HARLOW M. DAVIS.
